UNITED STATES PATENT OFFICE.

CHARLES R. JOHNSON, OF ALLEGHENY, AND HENRY JOHNSON, OF PITTSBURG, PENNSYLVANIA.

DETECTOR-RAIL.

SPECIFICATION forming part of Letters Patent No. 377,430, dated February 7, 1888.

Application filed December 2, 1886. Serial No. 220,437. (No model.)

To all whom it may concern:

Be it known that we, CHARLES R. JOHNSON, residing at Allegheny, and HENRY JOHNSON, residing at Pittsburg, in the county of Allegheny and State of Pennsylvania, subjects of the Queen of Great Britain, have invented or discovered certain new and useful Improvements in Detector-Rails, of which improvements the following is a specification.

10 In the accompanying drawings, which make part of this specification, Figure 1 is a view in side elevation of our improved detector-rail applied to a main-track rail. Fig. 2 is a detail view, on an enlarged scale, of our improved rail. Fig. 3 is a transverse sectional view on the line $x-x$, Fig. 2. Fig. 4 is a view, similar to Fig. 2, of a modification of the detector-rail.

15 The invention herein relates to certain improvements in that class of devices which are arranged alongside of a main rail, either in front of or behind the switch-points, and through their connection with the switch-operating mechanism will prevent any movement of the switch-points during the passage of a train 20 thereover.

25 The object of the invention herein is to so construct the detector-rail, with its operating mechanism, that said rail will not be readily blocked by dirt, snow, and ice, and hence will always be in readiness for use; and it is a further object of said invention to render the construction and applicability of the detector-rail as simple as possible, and thereby lessening its liability to breakage.

30 To these ends the invention consists in the construction and combination of parts, substantially as hereinafter described and claimed.

35 In the practice of our invention the rail or strip 1, which is of a length somewhat greater than the distance between the trucks of a car, or the trucks under the adjacent ends of two adjoining cars, is riveted or otherwise secured to a series of plates, 2, said plates being provided with a single or double inclined slot, 3, dependent upon the movement of the detector-rail—*i. e.*, whether the detector rail is

given a half or a complete throw. When a single slot is used, the slot begins at a point near the lower edge of the plate and extends upwardly at an inclination for a distance 50 equal to the movement of the rail, the length and inclination of the slot being dependent upon the longitudinal and vertical movements required in the rail. When the double slot is used, the portion of the slot near the lower 55 edge of the plate is made straight, and at the ends of this straight portion the inclined portions extend upwardly in the directions shown. Blocks 4, having one of their sides constructed to fit against the web of the main 60 rail 5 between the head and the flange thereof, are secured to said main rail, at intervals equal to the distance apart of the plates 2 on the rail 1, by bolts 6, passing through the blocks and the web of the rail. These bolts are provided 65 with stud-like heads 7, which project through the slots 3 in the plates 2, and serve as bearings for said plates.

The plate 2, nearest the switch-points or the switch-operating mechanism, is provided with 70 a stud, 8, to which the rod, or other mechanism connecting the detector-rail and switch-operating mechanism, is attached.

In using the plates having the single slot the rail is moved up above the tread of the 75 main-rail before the switch-points are shifted, is held there during such shifting of the points, and is moved back to normal position after the points have been shifted. The double-slotted plate is used when mechanism 80 independent of the switch-operating mechanism is used for shifting the detector-rail, and when operating switch-points the double-slotted plate is first thrown completely over, then the switch-points are shifted and the detector-rail returned to normal position. These movements of the detector-rail are in unison with the unlocking and locking of the switch mechanism.

It will be noticed that in the construction of 90 rail shown the operating mechanism—*i. e.*, the slots and studs—is so arranged as to be

free from all liability of becoming clogged by dirt, snow, or ice, and that the parts of the device are so small that their liability of breakage is reduced to a minimum.

5 We are aware that slotted detector-rails mounted in a groove or recess in a railway-chair are old, and hence make no claim to such construction.

We claim herein as our invention—

10 The combination of the main rail, a series of studs projecting from the web portion thereof,

a series of plates each provided with an angular slot, and a rail or strip secured to said plates, substantially as set forth.

In testimony whereof we have hereunto set 15
our hands.

CHARLES R. JOHNSON.
HENRY JOHNSON.
